CIRCUIT CONTROLLING DEVICE

John H. Wheelock, Fitzwilliam, N. H., and Ferdinand F. Humphreys, Caldwell, N. J., assignors to Signal Engineering & Manufacturing Company, New York, N. Y., a corporation of Massachusetts

Application January 3, 1938, Serial No. 183,058

8 Claims. (Cl. 200—97)

The present invention relates to circuit controlling devices of the type commonly known as relays, wherein the energization of a winding is utilized to perform a desired function in an electrical control circuit, separate from the circuit of the relay winding.

The object of the present invention is to provide a device of the above indicated character, which, when energized, will set in operation associated mechanism for bringing about a change in an electrical control circuit, within a definite time interval, entirely independent of the period of energization, or of deenergization, of the relay winding. The above and other advantageous features of the invention will hereinafter more fully appear from the following description, considered in connection with the accompanying drawings, in which:

Fig. 1 is a view in side elevation of a circuit controlling device embodying the invention.

Fig. 2 is a view in front elevation of the device of Fig. 1.

Fig. 3 is a fragmentary perspective view, showing the relation between certain of the parts of Fig. 1.

Figs. 4, 5 and 6 are diagrammatic views, illustrating the functioning of the device.

Fig. 7 is a fragmentary view, illustrating a modification in the form of the actuating mechanism.

Figs. 8, 9 and 10 are diagrammatic views, illustrating the functioning of the device, as modified.

Referring to Figs. 1 and 2, the device consists of an energizing winding 1 mounted on one leg of a U-shaped magnetic core 2, with an armature 3 pivotally mounted on the other core leg. An actuating rod 4 is pivotally connected at its lower end to the free end of the armature 3, 35 with the upper end of the rod 4 pivotally connected to an arm 5, mounted on a shaft 6 extending parallel to the pivotal axis of the armature 3.

A pawl 7 is pivotally mounted on a stud 8 carried by the arm 5, and a spring 9 surrounding the stud 8, serves to yieldingly maintain a tooth 10 of the pawl 7 in engagement with a tooth 11 provided on a disk 12, forming part of a sleeve 13 turnable on the shaft 6. A spring 14, surrounding the sleeve 13, has one end anchored 45 to a pin 15, while its other end tends to turn the sleeve in a clockwise direction, as viewed in Fig. 3, to maintain an extension 16 of the disk 12 in engagement with a stop pin 17. Normally, the position of the disk 12 is such that when the 50 armature 3 is down and the winding deenergized,

the tooth 10 of the pawl 7 will be in engagement with the tooth 11 of the disk 12.

The sleeve 13 provides an arm 18, to which the free end of the spring 14 is connected, and a second pawl 19 is mounted on the arm 18, 5 with a spring 20 urging the pawl 19 in the direction of the teeth 21 of a ratchet wheel 22, turnable on the shaft 6. The wheel 22 is connected to a gear 23, in mesh with a gear 24 on a shaft 25 extending parallel to the shaft 6. The shaft 10 25 carries a control member 26, composed of insulating material, and the member 26 provides cam projections 27. The ratio between the gears 23 and 24 is such that turning the ratchet wheel 22 through the angle of one tooth 21, will cause 15 the control member 26 to be turned through an angle equal to the displacement between the corresponding faces of adjacent projections 27.

One end of a flexible contact 28 bears on the control member 26 midway between adjacent 20 projections 27, and the contact 28 is normally separated from a second contact 29. The contacts 28 and 29 are connected in a control circuit, indicated diagrammatically in Fig. 4 as consisting of an electrical load 30, adapted to be 25 connected to a source 31 of electrical energy, upon closure of the contacts 28 and 29. In Fig. 4, the terminals of the winding 1 are shown as being adapted for connection to the source 31, in any suitable manner, as by means of a 30 switch 32.

While the winding 1 remains deenergized, the parts occupy the position of Figs. 3 and 4, and it is obvious that upon closure of the switch 32, 35 energization of the winding 1 will cause the armature 3 to pull up. As the armature 3 moves upwardly, as shown in Fig. 5, the engagement of the pawl tooth 10 with the disk tooth 11, turns the sleeve 13 in a counterclockwise direction, against the pull of the spring 14. This movement 40 of the sleeve 13 advances the pawl 19 over the surface of the ratchet wheel 22, and just after the pawl 19 slips over a tooth 21, but before the armature 3 has completed its upward movement, the upwardly extending end of the winding pawl 45 7 engages the stop pin 17.

As the armature 3 completes its upward movement in response to energization of the winding 1, the pin 17 turns the pawl 7 in a direction opposed to that in which it has been moved by 50 the arm 5, so as to disengage the pawl tooth 10 from the disk tooth 11, as indicated in Fig. 6. When this occurs, the sleeve 13 having been released from the winding pawl 7, is now free to be turned by the spring 14, until the extension 55

16 of the disk 12 engages the stop pin 17. Thus, the ratchet wheel 22 is turned by the driving pawl 19 through the displacement of one tooth 21, and the gears 23 and 24 cause the shaft 25 to be turned through an angle equal to the displacement between adjacent projections 27.

In Fig. 6, the disk 12 is shown as having moved to a position substantially midway between its extreme positions of Figs. 4 and 5, and the corresponding position of the control member 26 is such that a projection 27 thereof has moved the contact 28 into engagement with the contact 29, thereby closing the control circuit. However, the disk 12 continues to turn until it has returned to the position of Fig. 4, which movement is also imparted to the control member 26, so that the contact 28 passes off of the projection 27, to again open the control circuit. Thus, movement of the disk 12 from the position of Fig. 5 to the position of Fig. 6, is accompanied by making and breaking of the control circuit. If desired, a contact 29a that is normally in engagement with contact 28, can be substituted for the contact 29, as indicated in dotted lines in Fig. 4, it being evident that operation of the device will then cause the control circuit to be first broken, and then reestablished.

As previously pointed out, the interval during which the control circuit is closed or opened, as the case may be, is entirely independent of the period of energization, or deenergization of the winding 1. That is to say, the period of time during which the switch 32 may remain closed to energize the winding 1, bears no relation to the time interval which elapses following the release of the pawl 7, during which control member 26 turns from the position of Fig. 5 to the position of Fig. 6, and then to the position of Fig. 4.

In order to vary this time interval to meet various requirements of the circuit under control, the device provides an adjustable escapement mechanism, such as is shown for example, in Patent No. 2,077,099, issued April 13, 1937. This mechanism consists of step-up gearing 33 for driving a shaft 34 at a considerably greater speed than the shaft 25, with a toothed escapement wheel 35 mounted on the shaft 34. An escapement pawl 36 mounted on a shaft 37, serves to convert rotation of the shaft 34 into oscillatory movement of the shaft 37. An arm 38 extending from the shaft 37 provides a ball 39, received between a pair of spaced disks 40, freely mounted on a shaft 41, with the arm 38 being adjustable radially of the shaft 37. Oscillatory movement of the escapement shaft 37 therefore causes the disks 40 to also be oscillated, with the disks exerting a retarding action, in accordance with their amplitude of oscillation. Thus, by adjusting the position of the ball 39 at the end of the arm 38 between the disks 40, the duration of the turning movement of the control member 26 can be controlled.

Referring now to Fig. 7, there is shown a modified form of actuating device, wherein the disk 12 provides a second tooth 11a adjacent to the tooth 11. The tooth 10 of the pawl 7 is normally in engagement with the disk tooth 11, so that upward movement of the armature 3 in response to energization of the winding 1, serves to turn the disk 12 in a counterclockwise direction.

As the armature 3 completes its upward movement, the upwardly extending portion of the pawl 7 engages the stop pin 17, which turns the pawl just enough to release its tooth 10 from the

disk tooth 11. However, as the released disk 12 starts to turn in a clockwise direction under the force of the spring 14, the tooth 11a engages the pawl tooth 10, so that the disk can turn through only substantially one-half of its original displacement. The disk 12 will remain in its intermediate position as long as the armature 3 remains in its attracted position, through continued energization of the winding 1.

The above described functioning of the disk 12 with the extra tooth 11a, is shown diagrammatically in Figs. 8, 9 and 10, with reference to a circuit under the control of the contacts 28 and 29. In Fig. 8, the device is shown in its normal deenergized condition, with the pawl tooth 10 in engagement with the disk tooth 11, and with the control contacts 28 and 29 open. In Fig. 9, the pawl 7 is shown as having turned the disk 12 to its extreme position, wherein the pawl is just about to engage the stop pin 17. In this position, the winding pawl 19 has been advanced the space of one tooth on the ratchet wheel 22, but as yet there has been no turning movement imparted to the shaft 25 carrying the control member 26, so that the contacts 28 and 29 are still open.

In Fig. 10, the armature 3 is shown as being fully attracted, with the pawl 7 having been turned by its engagement with the pin 17, to disengage its tooth 10 from the first disk tooth 11. In this position of the pawl 7, which is maintained as long as the armature 3 remains attracted, the tooth 11a on the disk 12, has engaged the pawl tooth 10, so that the disk 12 has been permitted to only partially return to its original position. The degree of return movement permitted by the pawl 7 is such that the shaft 25 will be turned just enough to cause a projection 27 of the control member 26 to close the contacts 28 and 29. Obviously, the contacts 28 and 29 will remain closed until the winding 1 is deenergized, whereupon dropping of the armature 3 will permit the disk 12 to return to the original position of Fig. 8, as it follows the pawl 7 downwardly, thereby opening the contacts 28 and 29.

With the device functioning as shown in Figs. 8, 9 and 10, there will be a time lag between energization of the winding 1 and closure of the contacts 28 and 29, which does not occur until after the disk 12 has been turned by the pawl 7, and then released. The length of the time interval that elapses between energization of the winding 1 and closure of the contacts 28 and 29, can be controlled by the adjustable escapement device, previously described with reference to Fig. 3. This same time interval also enters into opening of the contacts 28 and 29, following deenergization of the winding and dropping of the armature 3.

From the foregoing, it is apparent that by the present invention there is provided a circuit controlling device which, when energized, will set in operation associated mechanism for controlling an electrical circuit within a definite time interval, entirely independent of the period of energization, or of deenergization, of the operating winding.

We claim:

1. An electrical circuit controlling device comprising a winding, a magnetic armature movable upon energization of said winding, relatively movable contacts incapable of direct movement by said armature, a mechanism for operating said contacts, a connection between said mechanism

- and said armature operative in response to movement of said armature to place said mechanism in condition to operate said contacts, but without imparting movement to said contacts, and means 5 for releasing said mechanism as said armature completes its movement, in response to energization of said winding to permit said mechanism to operate said contacts over a predetermined period.
2. An electrical circuit controlling device comprising a winding, a magnetic armature movable upon energization of said winding, relatively movable contacts incapable of direct movement by said armature, a mechanism for operating said contacts, a connection between said mechanism 10 and said armature operative in response to movement of said armature to place said mechanism in condition to operate said contacts, but without imparting movement to said contacts, and means for releasing said mechanism as said armature completes its movement, in response to energization of said winding, to permit said mechanism to operate said contacts over a period independent of the period of energization or deenergization of said winding.
- 25 3. An electrical circuit controlling device comprising a winding, a magnetic armature movable upon energization of said winding, relatively movable contacts incapable of direct movement by said armature, a wind-up mechanism for operating said contacts, a connection between said armature and mechanism to place said mechanism in a wound-up condition upon movement of said armature in response to energization of said winding, and means for releasing of said mechanism 30 while in a wound-up condition to permit it to operate said contacts after said armature has completed its movement.
4. An electrical circuit controlling device comprising a winding, a movable magnetic armature 40 directly associated with said winding, relatively movable contacts mechanically disassociated from said armature and winding, mechanism for operating said contacts and a connection between said armature and contact operating mechanism responsive to movement of said armature, upon energization of said winding to actuate said mechanism and cause it to operate said contacts over a predetermined period, after said armature has completed its movement in response to energization of said winding.
5. An electrical circuit controlling device comprising a winding, a movable magnetic armature directly associated with said winding, relatively 45 movable contacts mechanically disassociated from said armature and winding, mechanism for operating said contacts and a connection between said armature and contact operating mechanism responsive to movement of said armature, upon energization of said winding to actuate said mechanism and cause it to operate said contacts over a predetermined period, independent of the period of energization or deenergization of said winding.
6. An electrical circuit controlling device comprising a winding, a movable magnetic armature directly responsive to energization or deenergization of said winding, relatively movable contacts 50 mechanically disassociated from said armature, mechanism for operating said contacts, and a connection between said armature and contact operating mechanism responsive to movement of said armature in one direction, upon energization of said winding to operate said mechanism and thereby cause said contacts to operate over a predetermined period, irrespective of deenergization of said winding, and movement of said armature in the opposite direction.
7. An electrical circuit controlling device comprising a winding, a movable magnetic armature directly associated with said winding, relatively movable contacts entirely disassociated from said winding, a windup mechanism for operating said contacts, a connection between said armature and mechanism to place said mechanism in a wound-up condition upon movement of said armature in response to energization of said winding, and means for releasing said mechanism while in its wound-up condition, to cause said contacts to perform a sequence of operations effective only after said armature has completed its movement.
8. An electrical circuit controlling device comprising a winding, a movable magnetic armature directly associated with said winding, relatively 55 movable contacts entirely disassociated from said winding, a wind-up mechanism for operating said contacts, a connection between said armature and mechanism to place said mechanism in a wound-up condition upon movement of said armature in response to energization of said winding, and means for releasing said mechanism while in its wound-up condition, to cause said contacts to be moved relatively to each other, entirely irrespective of the position of said armature during such contact operation.
